CLAIM

The ornamental design for a pharmaceutical product container as shown and described.

DESCRIPTION

FIG. 1 is a bottom perspective view of a pharmaceutical product container shown without the security seal for clarity of illustration.

FIG. 2 is a bottom perspective view of the pharmaceutical product container.

FIG. 3 is a front side view of the pharmaceutical product container.

FIG. 4 is a back side view of the pharmaceutical product container.

FIG. 5 is a left side view of the pharmaceutical product container.

FIG. 6 is a right side view of the pharmaceutical product container.

FIG. 7 is a top view of the pharmaceutical product container.

FIG. 8 is a bottom view of the pharmaceutical product container.

FIG. 9 is a bottom perspective view of the pharmaceutical product container according to a second embodiment; and,

FIG. 10 is a bottom view of the pharmaceutical product container of FIG. 9.

1 Claim, 8 Drawing Sheets
